[57] CLAIM

The ornamental design for an agricultural spraying implement, substantially as shown.

DESCRIPTION

FIG. 1 is a top plan view of an agricultural spraying implement embodying my design;

FIG. 2 is a side elevational view thereof the opposite side being substantially a mirror image of the side shown herein except for the location of the chain and sprockets.

FIG. 3 is a rear elevational view thereof.

FIG. 4 is a front elevational view thereof.
